Primary Examiner — Katherine Glennon(74) *Attorney, Agent, or Firm* — Holtz, Holtz & Volek PC(57) **CLAIM**

The ornamental design for a watch case, as shown and described.

DESCRIPTION

FIG. 1 is a reduced-scale front, right side, bottom perspective view of a watch case showing our new design; FIG. 2 is front elevational view thereof; FIG. 3 is a rear elevational view thereof; FIG. 4 is a left side view thereof; FIG. 5 is a right side view thereof; FIG. 6 is a top plan view thereof; FIG. 7 is a bottom plan view thereof; and, FIG. 8 is a reference reduced-scale front elevational view thereof, with a watchband attached.

The broken lines are included for the purpose of illustrating the environmental structure and form no part of the claimed design.
